(57) **CLAIM**

The ornamental design for a watermelon pouch, substantially as shown and described.

DESCRIPTION

FIG. 1 is a front elevation view of a watermelon pouch according to a first embodiment of the present invention wherein the pouch is empty;

FIG. 2 is a front elevation view of a watermelon pouch according to a second embodiment of the present invention wherein the pouch is empty;

FIG. 3 is a front elevation view of the watermelon pouch of FIG. 2 wherein the pouch contains a watermelon, and the back elevation view being identical;

FIG. 4 is a left side elevation view that is normal to the view of the watermelon pouch as shown in FIG. 3, the right side elevation view being a mirror image thereof;

FIG. 5 is a bottom plan view of the watermelon pouch shown in FIG. 3;

FIG. 6A is a top plan view of the watermelon pouch shown in FIG. 3;

FIG. 6B is a top plan view of the watermelon pouch shown in FIG. 3 with the opening expanded;

FIG. 7 is a front perspective view of the watermelon pouch shown in FIG. 3; and,

FIG. 8 is a bottom perspective view of the watermelon pouch shown in FIG. 3.

The broken lines are for illustrative purposes and represent environmental structure and unclaimed portions of the invention and therefore form no part of the claimed design.
